UNITED STATES PATENT OFFICE.

RUDOLF CHILLINGWORTH, OF NEW YORK, N. Y.

AEROPLANE.

Application filed June 12, 1924. Serial No. 719,480.

This invention relates to aeroplanes and has for its particular object to provide means which will so co-operate during the flight of the aeroplane as to bring about 5 more secure means for maintaining the normal and safety position of the aeroplane during its flight, or during its ascent or descent.

For this purpose, my invention consists, 10 in general, of means whereby the air is compressed and compacted in a way so as to form air columns of compacted air at the rear or at the bottom of an aeroplane. Such columns of compressed air, arranged within 15 the surrounding air, with a part of the aeroplane on top or at the end of the column, serve to hold the aeroplane in position and thereby prevent a wobbling or uncontrolled 20 action of the aeroplane. As a result of this improvement, the use of aeroplanes is made safer than heretofore, since many accidents heretofore have resulted in that aeroplanes enter air pockets, or are subjected to currents which have an effect upon the movement 25 of the aeroplane, so as to cause such aeroplanes to get beyond the control of the pilot. But with the plane, so to say, resting upon this air column, an air quasi anchorage is obtained, so that when the aeroplane enters 30 an air pocket or is subjected to any currents of the air, any wobbling that might, under ordinary conditions take place, is prevented by this anchorage. The compression or compacting of the air into the column 35 forms a guiding support produced by the aeroplane itself, on which support the aeroplane continuously and progressively anchors. While this permits a lateral sway of the plane, it hinders and prevents a forward 40 or backward drop or plunge.

The invention consists further in certain improvements in aeroplane structures, which consists essentially in providing a water-tight compartment for the operating mechanism 45 of the propeller for the pilot, for the passengers, and attendants, as also, if desired, for the steering gear, and the surrounding of this water-tight compartment or inner tube with an outer tube. The annular space 50 between the inner and outer tubes serves to guide the air, which is being compacted and compressed by a suitable propeller, so that the continuation of this annular space between the two tubes serves to form the compacted air column hereinabove referred to. 55 This particular improvement in aeroplanes

provides a water-tight compartment on the one hand and the compacting-air tube on the other, though either of these features may be independently used as they form independent improvements in the art. Between the inner and outer tubes, suitable strengthening members are provided, which serve to hold the tubes in their respective positions. Exterior to the outer tube, the usual skeleton and frame-work of an aeroplane is provided.

The invention consists further of certain features which will be hereinafter described. Among others, the combination of an air compacting propeller with the aeroplane driving propeller; also the particular arrangement of the aeroplane driving propeller to bring about exterior air columns, exterior to the inner air column. Certain other features of the invention will be more fully described hereinafter, all of the parts thereof shown in the annexed drawings, and the invention finally pointed out in the claims.

In the accompanying drawings,

Figure 1 is a vertical sectional view of the air compacting members to compact the air and form an air column,

Figure 2 is a front view of Figure 1,

Figure 3 is a view like that of Figure 1, but provided with exterior propelling vanes,

Figure 4 is a view similar to that of Figure 3, but showing my improved propeller vanes, also showing how the propeller vanes provide an outer column of compacted air,

Figure 5 is an edge view of a modification,

Figure 6 is a plan view partly in section of an aeroplane embodying the water-tight compartment and surrounded by the air compacting tube,

Figure 7 is a front view of Figure 6, and

Figure 8 is a side view of Figure 6.

Similar characters of reference indicate corresponding parts throughout the various views.

Referring to the drawings and more particularly to Figures 1 and 2, a suitable shaft 10 is provided with spider arms 11, in the drawing shown as six in number. These spider arms support at their peripheral ends a circular rim 12; in front of the spider arms, a conical cap 13 is provided to give as little resistance to the air as possible. Preferably the shaft 10, the spider arms 11, the rim 12 and the cap 13, are all preferably made of one piece. Between the cap

13 and the rim 12, there are arranged in the embodiment shown, six (6) vanes or blades 14, which curve from the front part of the rim inwardly and downwardly to the rear part of the rim, and at their lowermost ends abut against the spider arms 11. These blades are preferably six in number and in consequence there are six open spaces at the front, and also six open spaces at the rear; 10 the latter open spaces are formed between the spider arms 11. The blades themselves are suitably curved and take up the space between the cap and the rim. Looking at Figure 2, the open spaces are above and below the blades 14. Rearwardly of the rim, an extension 15 is provided, which serves to guide the compacted air. Any suitable operating means may be provided to rotate the shaft at a suitable speed. When such 20 shaft is rotated and the spider arms, cap and rim, and blades rotated therewith, the air that enters the front of the blades is guided rearwardly out of the openings between the spider arms and compacted as it leaves the 25 rear of the spider arms and the rear of the extension of the rim. This compacting serves to bring together the atoms or molecules of the air in a cylindrical compressed mass, which might be referred to as an air 30 column. The cylindrical mass of air is formed and controlled by the means described. Also the disturbing air at the front is removed. This generated compressed or compacted air of cylindrical contour, exists 35 within the general air atmosphere, the only difference between the general atmospheric air and this column of air being that the column is of more compressed and compacted form or constituency of cubical mass. 40 It is a permanent guide, always or continuously generated, which, while it has an anchorage greater than the disturbing influences, holds the aeroplane in position. It has also a radial anchorage or action. The 45 rotating blades act in the nature of a corkscrew entering the air as the aeroplane proceeds, and the blades compact the air to form the air column at the rear of the aeroplane. The general object of this air column 50 is that as the blades move through the air and compact the air, these blades with their frame rest, so to say, upon this compacted column, and the general idea is that the aeroplane structure thereby finds an anchorage 55 upon this air column. As a result of this action, should the aeroplane strike any air pocket or any eddy currents which would, under ordinary circumstances, cause it to wobble or to take a dangerous turn, this 60 combination and co-operation of the air column with the mechanism serves to hold the aeroplane securely in position and overcomes thereby any action of air pockets, or eddy currents.

In Figure 1, the compacted air is shown

by the dotted effect showing a cylindrical column of compacted air. This column, of course, extends quite a distance, depending upon the relativity of the compacted column and the surrounding atmosphere.

In Figure 3 is shown the structure of Figures 1 and 2, provided, however, with a propeller exterior to the rim 12 and its extension 15 of the air compacting means. This propeller 18 in Figure 3 is shown of ordinary form or shape and acts like the usual propellers heretofore used with aeroplanes.

In Figures 4 and 5, a particular kind of propeller is shown exterior to the air compacting means. This propeller has a bent-over portion at its periphery, which serves to captivate the air and so to raise the efficiency of the propulsion of the blades and discharge the air on the line 20-21, and thereby form an outer or exterior air column 85 surrounding that of the air column formed by the air compacting means. The inner air compacting means and the outer air compacting means thereby give a core of compacted air and a surrounding sleeve of compacted air. The outer sleeve of compacted air serves to maintain for a greater length of time the compacted inner air column core, and prevents its diffusion into the surrounding atmosphere. The arrow 19 in Figs. 3, 4 and 5 shows the direction of rotation. In Figure 4 only four blades are shown. Any number of blades may be used for either propeller.

In Figures 6, 7 and 8 are shown figures of an aeroplane. The center portion thereof consists of a watertight compartment, in which the mechanism for moving the propeller is arranged, in which also a space is provided for the pilot, as also space for the passengers, or attendants. The propelling mechanism is indicated in general by the character 22, although not shown in detail, as the same is well-known. The place for the pilot is indicated by 23; the place for the passengers by 24; the place for the steering gear at 25. All these different places are arranged in the air-tight compartment 30, so that in the event the aeroplane should encounter an accident and fall upon the surface of the water, it will not sink, but will float, and hold harmless the persons therein from the entrance of water. The joints of the doors, windows, etc., are also air-tight. This compartment 30 is arranged of general 113 tubular shape and forms the inner tube of the aeroplane. Exterior to this inner tube is arranged an outer tube 26, the inner and outer tubes being held together by the ribs or bars 27. The propeller 29 is arranged at 120 the front of the aeroplane and when it is operated it serves not alone to propel the plane but to compress and compact the air in the space between the inner tube 30 and outer tube 26. At the rear of the outer tube

the compacted and compressed air forming the air column hereinabove defined is provided, which serves, as hereinbefore explained, as an anchoring means to overcome the action of any eddy currents or air pockets which the plane may encounter. A stabilizing means is thereby provided. Both inner series of blades and outer series of blades when arranged as described, serve to stabilize the operation of the aeroplane. In Figure 1 for instance, both inner and outer tube is rotatable, whereas in Figure 6 for instance, the inner and outer tubes are fixed. In Figure 1 is shown a combination of an air compressor, and a propeller. In Figure 6, an ordinary propeller is shown, but it is understood that to compact the air, an air compressor is used, either like Figure 1, or Figure 3, or Figure 5. The exhauster action assists in the progress of the plane. The exhauster-compressor acts in respect to the cubical dimensions, rather than as a planetary action, as the planes, serves also to anchor and act against the wobbling of the plane. A plurality of the devices described may be applied to an aeroplane, and these can be either horizontal or vertical. The propeller shown in Figure 1 is adapted to be placed in vertical or horizontal position. Surrounding the outer tube is the usual frame-work and planes of the aeroplane, and of course, instead of one plane, a series thereof may be provided. These are not further described in detail as they form no part of my invention.

The air compacting means can be arranged to discharge the compacted air horizontally as shown, or can be also arranged to discharge it vertically.

In Figure 3, the outer blades 18, are shown as set back out of the plane of rotation of the inner blades 14, in order to show by the drawings the curvature of the parts. It is preferable to have the base curvature of the outer blades 18, of the same configuration as the peripheral curvature of the inner blades, and have the outer blades form, so to say, a continuation of the inner blades, both blades being in the same plane of rotation. By this arrangement the air is not disturbed except in parallelism. But the outer blades could be arranged set back as shown. In either case, a rim 15 to form an extension, may be provided.

The turned over ends of the outer blades increase the efficiency of the propelling effect.

In Figure 6, the part indicated by 26^a, is the outer tube broken away.

I have shown various embodiments of my invention but changes may be made without departing from the spirit of same, as defined in the appended claims.

In a preferable form, the rim 12, and its interior and exterior surfaces act as a support for the inner blades and the outer

blades, and the bases of the outer blades, conform to the peripheral portions of the inner blades. Suitable guideways at the interior and exterior of the rim can be arranged whereby the inner and outer blades 70 may be slid into place and locked therein. The rim acts thereby as a common carrying member for both inner and outer blades.

I claim as new:

1. In an aeroplane, air compacting means 75 comprising a shaft, blades arranged thereon, a rim surrounding the blades and extending beyond the rear ends thereof, and a second series of blades carried by the outer face of the rim at the rear edge of the rim, and having their forward edges extending in a plane 80 slightly forward of the inner edges of the inner blades.

2. In an aeroplane, air compacting means comprising a shaft, blades arranged thereon 85 and having their front and rear edges in a longitudinal plane with the adjoining blades, a rim surrounding the blades and extending beyond the rear ends thereof, and a second series of blades carried by the outer face of 90 the rim at the rear edge thereof, and having their forward edges extending slightly beyond a plane with the rear edges of the inner blades.

3. In an aeroplane, air compacting means 95 comprising a shaft, blades arranged thereon, a rim surrounding the blades, a second rim carried by the outer face of the first rim, and a second series of blades carried by the outer face of the second rim, and having 100 their forward edges extending a slight distance forward of the rear edges of the inner blades.

4. In a aeroplane, air compacting means comprising an enlarged shaft having a conical cap for diverting air outwardly, blades arranged on said shaft in rear of said cap, a rim surrounding and carried by the blades, and having a rear extension extending a considerable distance beyond the rear edges of 110 the blades, and a second series of blades carried by the outer face of the rim at the rear edge thereof and having their forward edges extending in a plane slightly forward of the rear edges of the inner blades. 115

5. In an aeroplane, air compacting means comprising an enlarged shaft having a conical cap for diverting air outwardly, blades arranged on said shaft in rear of said cap, a rim surrounding and carried by said blades, a second rim surrounding the edge of the first rim and extending a considerable distance in rear thereof, and a second series of blades carried by the outer face of the second rim and having their forward edges extending slightly beyond a plane with the rear edges of the inner blades. 120

In testimony that I claim the foregoing as my invention, I have signed my name hereto.

RUDOLF CHILLINGWORTH.
